ERNEST KAUFMANN, OF PHILADELPHIA, PENNSYLVANIA.

Letters Patent No. 70,441, dated November 5, 1867.

IMPROVED TABLE-URN.

The Schedule referred to in these Letters Patent and making part of the same.

TO ALL WHOM IT MAY CONCERN:

Be it known that I, ERNEST KAUFMANN, of No. 248 North Eighth street, Philadelphia, in the county of Philadelphia, in the State of Pennsylvania, have invented a new and improved Table-Urn; and I do hereby declare that the following is a full, clear, and exact description thereof, which will enable those skilled in the art to make and use the same, reference being had to the accompanying drawing, forming part of this specification, in which drawing—

Figure 1 represents a vertical central section of this invention.

Figure 2 is a horizontal section of the same.

Similar letters indicate corresponding parts.

This invention relates to an urn in which different beverages, such as coffee, tea, or chocolate, can be prepared simultaneously, or in which coffee, tea, milk, and other liquids can be heated simultaneously, each liquid being kept in a separate chamber, provided with a faucet, so that the same can be drawn off as required.

The urn rests upon a stand, provided with a socket or platform to support a lamp, and it is so arranged that it can be freely revolved on said stand, and that that part of the urn from which the liquid is to be drawn can be readily brought opposite the person who intends to draw the liquid, without the necessity of turning the whole device, stand and all.

The interior of the urn is divided into two or more chambers, each being provided with a separate faucet, so that different liquids, such as milk and coffee, can be heated simultaneously, and each liquid can be drawn off as the same may be required.

A represents an urn made of metal, porcelain, or any other suitable material, in a cylindrical or any other desirable form or shape. This urn rests upon a stand, B, and it is provided with an annular lip, a, which projects under two or more ears b, which are fastened to and extend from the top edge of the stand, as clearly shown in the drawing.

By these means the urn can be readily turned on its stand in either direction, so that when the same is placed on a table, the faucet which serves to draw off the contents of said urn can be readily brought opposite the person desiring to draw off the contents, without the necessity of turning the stand together with the urn. If desired, the friction between the stand and the urn may be reduced by interposing friction-rollers or casters.

By this arrangement a table-urn is obtained which is very convenient, particularly in large families or hotels, where the urn necessarily must be large and heavy, and the operation of turning the same, together with its stand, on the table-cloth would be attended with some difficulty. It must be remarked that the arrangement of parts necessary for turning the urn independent of its stand might be changed. It might be made to turn on a central pivot, although in this case the operation of applying heat from below would be impeded, or the urn might be suspended from an arm above, and made to turn on a ring; but neither of these arrangements would be quite as desirable as the arrangement shown in the drawings.

The stand B is provided with a central socket or platform, C, to receive or support a lamp, D, which serves to heat the contents of the urn. The interior of the urn is partitioned off in two or more compartments or chambers e, each of which is provided with a distinct faucet, E, so that coffee, tea, chocolate, or other beverages can be prepared simultaneously, or that milk, tea, coffee, and other liquids can be heated simultaneously, and the contents of each chamber can be drawn off as the same may be required.

In order to increase the heating surface of the urn, it may be provided with one or more vertical flues, or a central flue may be applied, which serves as the chimney to carry off from the lamp the products of combustion and to increase the draught. This central flue could also be used to support a bearing for a vertical pin, if it should be desired to revolve the urn on its centre instead of on the annular rim or lip a. Each compartment is provided with a separate cover, so that the rapid evaporation of the liquids, and the escape or the commingling of the aroma, are prevented.

What I claim as new, and desire to secure by Letters Patent, is—

1. A table-urn which can be revolved on its stand, and is provided with two or more compartments or chambers e and faucets E, substantially as and for the purpose set forth.

2. The arrangement and combination of an urn, A, with two or more compartments e, annular lip a, stand B, ears b, lamp D, and faucets E, all constructed and operating substantially as and for the purpose shown and described.

Witnesses:—
